UNITED STATES PATENT OFFICE.

EDWARD L. VAN VLEET, OF GOODLAND, KANSAS.

GRAIN-DRILL CLEANER.

1,262,877.

Specification of Letters Patent. Patented Apr. 16, 1918.

Application filed August 29, 1916. Serial No. 117,531.

To all whom it may concern:

Be it known that I, EDWARD L. VAN VLEET, a citizen of the United States, residing at Goodland, in the county of Sherman and State of Kansas, have invented certain new and useful Improvements in Grain-Drill Cleaners, of which the following is a specification.

This invention relates to picker attachments for drills and the object of the same is to provide a device as specified that is simple in construction, efficient in operation and consists of the minimum number of parts.

With these and other objects in view, this invention consists of certain novel constructions, combinations and arrangement of parts, as will be hereinafter fully described and claimed.

In the accompanying drawings:

Figure 1 is a view in end elevation of my device in connection with a drill.

Fig. 2 is a top plan view of the same as shown in Fig. 1.

Fig. 3 is a fragmentary longitudinal sectional view taken through a portion of one of the shaft supporting brackets.

Referring to the parts by reference numerals, the frame of the drill is designated by the numeral 10, the axle by the numeral 11 and the supporting wheels by the numeral 12. The picker proper comprises a shaft 13 having secured thereon at uniformly spaced intervals the pickers 14. This shaft 13 is rotatably carried by the frame 10, the supporting arms 15 having the castings 16 at the lower end thereof through which the shaft 13 is passed. These castings are at uniformly spaced intervals on the shaft 13 between the pickers 14. A crown gear 17 is keyed to the shaft 13 adjacent one end thereof and a substantially U-shaped bracket 18 is also carried by this shaft 13 adjacent the ends of the same that has keyed thereto the crown gear 17. A plurality of collars 19 are keyed to the shaft 13 to retain the crown gear 17 and the bracket 18 in position as clearly shown in Fig. 2. On the axle 11 is a crown gear 20 and also

a substantially U-shaped bracket 21, the said gear and bracket being secured in the desired position on the axle by means of the keyed collars 22. It is to be understood that the gears 17 and 20 are keyed to the

shaft 13 and axle 17 respectively, for rotation therewith. The substantially U-shaped brackets 21 has formed therein an elongated slot 23 and in alignment therewith is an opening formed in the bracket 18. A shaft, designated in its entirety by the numeral 24, and comprising the small section 25 and the relatively large section 26 is journaled through this slot 23 and the opening aforementioned. A spur gear is secured fast to the reduced portion 25 of the shaft and designated by the numeral 27, the same being in mesh with the crown gear 17 and a similar gear, designated by the numeral 28 is fast to the opposite end of the shaft 24 and is in mesh with the crown gear 20. Therefore by rotation of the axle 18, the shaft 13 is rotated therewith by means of the shaft 18 and the intermeshing gears 17 and 28 and 20.

I have provided a means whereby the shaft 11 can be rotated independently of the shaft 13, the same comprising a pedal 29 that is pivotally carried by the spaced ears 30 on the frame 10 and terminates in a forked end 31 that embraces the large portion 26 of the shaft 24. As has been previously set forth, the enlarged portion 26 of the shaft 24 above mentioned is journaled through the slot 23 in the bracket 21 and is normally retained in such a position in said shaft as to retain the spur gear 28 that is secured thereto in mesh with the crown gear 20. This retaining means comprises a strip 32 that passes through a slot 33 formed in the bracket 21 and projections 34 are formed on this bracket 21 to receive one end of the bolts 35 each of which has the opposite end thereof passed through the strip 32. Coil springs 36 are wound about these bolts 35, the said springs being of the expansible type and normally move the shaft 24 so as to retain the spur gear 28 keyed thereon in mesh with the crown gear 20.

It is obvious that when it is desired to have the axle 11 rotate independently of the picker all that is necessary is to apply pressure on the pedal 29 and thus move the shaft 24 so as to move the spur gear out of mesh with the crown gear 20. It is to be understood that the opening in the bracket 18 through which the reduced portion 25 of the shaft 24 is journaled is of such size as to permit slight

movement of the shaft for this desired function.

It is to be noted that the pin 32 in the slot 33 is limited in its movement by the slot 5 so that the pin will not force the shaft against one end wall of the slot 23 and thus bind the shaft and prevent the ready rotation thereof.

It is obvious that minor changes may be 10 made in the form and construction of this invention without departing from the material parts thereof. It is therefore not wished to confine the invention to the exact form herein shown and described, but it is 15 wished to include all such as properly come within the scope claimed.

I claim:

1. In combination with a drill having a frame, supporting wheels therefor and an 20 axle having a gear keyed thereto and a bracket thereon, of a rotatable picker comprising a shaft and a series of picking elements, a substantially U-shaped bracket on said shaft, a gear wheel keyed to said shaft, 25 a second shaft journaled through said bracket and having a gear wheel thereon in mesh with said gear wheel on said picker, a second gear on said second mentioned shaft and in engagement with said gear on 30 said axle whereby by the rotation of said axle rotary movement will be imparted to said picker, means on said bracket on said axle and in engagement with said second shaft to normally retain certain of said gears in mesh and means for moving said

second mentioned shaft to move said last 35 mentioned gears out of mesh.

2. In combination with a drill including an axle, of a rotatable picker, means to rotate said picker including a shaft having a gear wheel on one end thereof in mesh 40 with a gear wheel keyed to said axle, a support for said shaft having an opening therein through which said shaft passes, said support also having a slot formed therein in communication with said opening, a pin in 45 said slot and in engagement with said shaft, a pair of coil springs in connection with said pin for normally urging the same into engagement with said shaft to retain said gear wheel in mesh and means for moving said 50 shaft in said opening in said support against the tension of said springs to move said gears out of mesh.

3. In combination with a drill having a gear keyed to the main axle thereof, of a 55 rotatable picker, a shaft for imparting rotary movement to said picker having a gear thereon, a bracket carried by said main axle and means on said bracket for normally retaining said gears in mesh and a second 60 means for moving said gears out of mesh as and for the purpose set forth.

In testimony whereof I affix my signature in presence of two witnesses.

EDWARD L. VAN VLEET.
